Kevin Prince**CLAIM**

We claim the ornamental design for a jacket, as shown and described.

DESCRIPTION

FIG. 1 is a perspective view of a jacket, showing our new design in a closed configuration;

FIG. 2 is a rear elevational view of FIG. 1;

FIG. 3 is a front elevational view of FIG. 1;

FIG. 4 is a left-side elevational view of FIG. 1, the right-side elevational view being a mirror image thereof;

FIG. 5 is a top plan view of FIG. 1;

FIG. 6 is a bottom plan view of FIG. 1;

FIG. 7 is a perspective view thereof; and,

FIG. 8 is a front elevational view of FIG. 7.

The broken line showing of a person in FIG. 1 represent environment and forms no part of the claimed design. The remaining broken lines in the figures represent stitching and form part of the claimed design.
